UNITED STATES PATENT OFFICE.

GROVER R. GREENSLADE, OF PITTSBURGH, PENNSYLVANIA, ASSIGNOR TO J. ROGERS FLANNERY, OF PITTSBURGH, PENNSYLVANIA.

X-RAY TUBE.

Application filed May 24, 1922. Serial No. 563,294.

To all whom it may concern:

Be it known that I, GROVER R. GREENSLADE, a citizen of the United States, and a resident of Pittsburgh, in the county of Allegheny and State of Pennsylvania, have invented a new and useful Improvement in X-Ray Tubes, of which the following is a specification.

The invention relates to X-ray tubes. Its objects are to provide an X-ray tube which acts to rectify the current even at very high voltages, thus dispensing with the use of outside rectifiers and enabling the associated and control apparatus to be simplified; which is more durable than similar tubes as heretofore constructed, from the fact that it requires no heated filament associated with the cathode; and which can operate on a lower voltage than prior forms of X-ray tubes, and hence reduces the liability of burning the patient.

In the accompanying drawing Fig. 1 shows the improved X-ray tube in section, and Fig. 2 is an enlarged detail view of the electrodes.

The tube comprises a vessel 1, which may be of the usual form and is exhausted to any degree desired. In this tube is the cathode or mirror 2 and the anode or target 3, which are connected to the outside circuit by simple leading-in wires sealed in the ends of the tube in the usual way.

Rectifying X-ray tubes as heretofore constructed have had associated with the cathode a filament arranged to be heated to incandescence by additional circuit connections through one end of the tube and supplied with a heating current either from a storage battery or from taps taken off the secondary of the voltage increasing transformer, said hot filament radiating electrons or other emissions which form a unilateral conducting path to the anode. The life of such filaments, however, is limited, and to heat the same requires additional leading-in wires and circuit arrangements and devices. Furthermore such tubes do not operate at very high voltages. There is a certain limit of permissible voltage

above which such tubes begin to flutter and hence cease to rectify.

In the improved X-ray tube, the hot filament and the circuit connections to it are entirely dispensed with, and a unilaterally conducting path, or at least one having greater conductivity in one direction than in the other, between the cathode and anode is provided by the emissions or radiations from a radio-active substance or substances associated with the cathode or with both the cathode and anode. The radio-active substance may be radium, uranium, actinium, thorium, or other radio-active substance or substances, or compounds thereof. Such substance or substances may be associated with the electrodes in any suitable way, such as coating or painting the compound on the face of a metallic electrode, or fusing the radio-active material thereto, or alloying it therewith.

The above radio-active materials and their disintegration products emit three forms of rays, to-wit, gamma rays, which are oscillatory disturbances of the character of light rays but of very high frequency, alpha rays, which are small particles, or, strictly speaking, atoms of helium gas and carry positive electrical charges, and beta rays which are electrons and constitute negative electrical charges. Hence the radio-active materials or products are preferably associated with the cathode in a manner to control the emission of the alpha rays, in order that the particles composing such rays will not fill the space in the tube which would destroy the unilateral conductive characteristic of the tube. A convenient way of doing this is illustrated in the drawing, in which the body of the cathode 2 may be of any suitable metal, although for the purpose of lightness aluminum or some similar metal is preferred. It has secured to its mirror face a very thin metal sheet 4, such as a thin foil of aluminum or the like, which forms a screen for the alpha rays, leaving a space between said screen and the body of the cathode which contains the radio-active material. By choosing a screen of material of

the proper density and proper thickness the alpha rays can be entirely cut off, without seriously interfering with the passage of the beta rays, and with no or little interference with the passage of the gamma rays. These rays bombard the anode or target. The beta rays produce the primary X-rays and are the principal effective rays. The gamma rays produce secondary X-rays but these are not as effective or as important as the X-rays produced by the bombardment of the anode by the beta rays. It has been found that a foil of aluminum of 7/100 millimeters in thickness gives good practical results, that is, it intercepts all or substantially all the alpha rays and only a small amount of the beta rays. The screen, however, can be of material other than aluminum, but if made of a denser metal it must be made thinner than above specified.

A cathode of the character described is substantially a cold cathode. Since there is no hot filament, the tube is more durable than present forms of X-ray rectifying tubes. It requires no circuit connections to it other than the simple circuit connections for the main current, and hence the outside apparatus may be of the simplest character and provided with the simplest form of controlling mechanism. It is effective in producing between the electrodes a conducting path which is of greater resistance in one direction than in the other, and thus acts to effectively rectify the current. As a result outside rectifiers can be entirely dispensed with. Additionally the tube does not begin to flutter at even high voltages, and therefore can be used without outside rectifiers at voltages much higher than the present form of hot filament X-ray tubes. Furthermore the conducting path produced by the radio-active emissions permits the high tension electric current to pass with greater ease so that the tube can be used with a current of lower voltage than with prior forms of tubes, thus reducing the danger of burning the patient and making the apparatus as a whole easier to handle and safer to use, and even safe for use by relatively unskilled operators.

The effect of the radio-active substance on the cathode may be enhanced by applying to the anode another radio-active substance which emits rays which carry opposite electrical charges from those permitted to be radiated by the radio-active substance in the cathode. For instance, if the cathode has associated with it a radio-active substance which emits only beta rays, or is screened or controlled to permit of the passage only, or substantially only, of beta rays, which constitute negative electrical charges, the anode should have applied thereto or associated therewith a radio-active substance, for example polonium, as

indicated at 6, Fig. 2, which emits only or largely alpha rays, which carry positive electrical charges. The same effect can be produced by applying to the anode a radioactive substance which emits rays of several kinds, and so screening or otherwise controlling this substance as to emit only or largely rays which carry positive electrical charges. Thus by having rays emitted by the two electrodes which constitute 75 or carry opposite electrical charges, the unilateral conductive characteristics of the intervening space is enhanced.

The invention is not dependent upon any particular degree of exhaustion of the tube. 80 The tube may be exhausted either wholly or partially, but need be exhausted only to such degree that ionization is reduced to a point below that at which the space between the electrodes is rendered of equal conductivity 85 in both directions. The invention is also applicable to tubes containing gases which have the characteristic that notwithstanding that ionization occurs, the space between the electrodes is nevertheless of greater conductivity in one direction than in the other. 90

I claim:

1. In an X-ray tube, a cathode and an anode, a radio-active substance associated with the cathode and being of a character 95 that its emissions constitute or carry opposite electrical charges, and means for intercepting one kind of said emissions and permitting the passage of the other kind of said emissions to thereby render the space 100 between the cathode and anode of greater conductivity in one direction than in the other.

2. In an X-ray tube, a cathode and an anode, a radio-active substance associated 105 with the cathode and of a character to emit both alpha and beta rays, and means to intercept the alpha rays to thereby render the space between the cathode and anode of greater conductivity in one direction than 110 in the other.

3. In an X-ray tube, a cathode and an anode, a radio-active substance applied to 115 said cathode and of a character to emit both alpha and beta rays, and a thin metal screen enclosing said radio-active substance and serving to intercept the alpha rays emitted by said radio-active substance and permitting the passage of the beta rays to bombard the anode and produce X-rays. 120

4. In a gap device for the passage of electrical current, an electrode having an internal pocket or recess, and a radio-active substance disposed within the pocket and encased in the body of said electrode, whereby the emissions of said radio-active substance in order to escape must necessarily pass through a portion of said body. 125

5. In a gap device for the passage of electrical current an electrode, a radio-active 130

substance associated therewith and of a kind emitting both alpha and beta rays, and a screen over said radio-active substance and serving to suppress one kind of said rays. 10

5 6. In a gap device for the passage of electrical current, an electrode, a radio-active substance associated therewith and emitting

both alpha and beta rays, and a thin metal screen enclosing said radio-active substance and serving to suppress the alpha rays. 10

In testimony whereof, I sign my name.

GROVER R. GREENSLADE.

Witness:

EDWIN O. JOHNS.
